UNITED STATES PATENT OFFICE.

THOMAS F. CROCKER, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed January 16, 1925. Serial No. 2,744.

This invention relates to telephone systems in general, but more particularly to small automatic telephone systems. In such systems, an operator may be required to give 5 complaint and information service, to complete rural and toll connections, and also to give other miscellaneous service. The principal object of this invention is to provide simple and efficient circuits for the operator's 10 switchboard for giving these various kinds of service.

The features of this invention will be fully described in connection with the explanation of the different operations to be performed 15 by the operator, reference being had to the accompanying drawings.

Referring now to the drawings, the three figures placed end to end in numerical order show enough of the essential elements of a 20 telephone system to illustrate and explain the invention. Fig. 1 shows the circuits of the apparatus at the operator's position; while Figs. 2 and 3 combined show the circuits and connections of the necessary 25 switches to complete a call from one automatic telephone to another automatic telephone, to complete a call from an automatic telephone to an operator for information, rural, or toll service, or to complete a call 30 from the operator to any automatic telephone.

The apparatus will now be explained more in detail. For the sake of convenience, the automatic apparatus on Figs. 2 and 3 will be 35 described first. The substation B in Fig. 2 is an ordinary automatic telephone having a line, comprising conductors 122 and 123, to the automatic exchange. Associated with each telephone line at the automatic exchange 40 is an individual line switch such as C, in Fig. 2. The line switches are of the well known rotary type, in which the wipers have no normal position and move in a forward direction only. The total number of line switches may 45 be divided into several groups, each group having access to a group of selectors. When a call is initiated at a substation, the line switch associated with that substation is operated to hunt an idle selector.

50 The selectors, one of which is shown in Fig. 2, designated D, are of the well known Strowger vertical and rotary type. The selectors have access to groups of connectors,

each level of the selector banks being assigned to a certain group. 55

The banks of the individual connectors of any one group are multiplied together and serve as the terminating point for the subscribers' lines. Each group may accommodate 100 lines in the ultimate. Besides the several groups of ordinary connectors there may be one or more groups of rotary connectors accessible from a certain one or more selector levels. The rotary connectors, one of which is shown in Fig. 3, denoted by E, besides accommodating individual lines, may have access to groups of lines, all the lines of any one group having the same directory number. In this case, the rotary connector wipers, after picking out the desired group 60 of lines in the connector bank, commence an automatic rotary trunk hunting movement to pick out the first idle trunk of the group. A group of lines may extend to a private subscriber who has several telephones; or a group of lines may be desired for each kind of special service to an operator at the automatic exchange. Substation B' is an illustration 65 of an individual line terminating in the banks of the rotary connector E. The line comprising conductors 32, 33, and 34 is one 70 line of a certain group of lines for special service to the operator.

Having described the automatic exchange 75 switches, the description of the apparatus at the operator's position will be given. In a small automatic exchange such as is being described, several groups of trunks from rotary connector levels may terminate at an operator's position to be used for special service. 80 Each group of trunks may be reserved for a certain kind of service. One group of trunks may be reserved for information, another group for toll service, another group for complaint, and other groups for such services 85 as may be required. In the drawing, Fig. 1, the trunk comprising conductors 32, 33 and 34 may represent one trunk of a group of trunks reserved for rural service. The trunk terminates at the jack J² with its associated circuit TC'. The drop 3 serves to signal the operator. The other trunks to the operator 90 for information, and the several other special services are identical with this described 95 trunk and terminate at jacks like jack J². The line represented in Fig. 1 by conductors 100 105

100

tors 10 and 11 and terminating at the jack J is one of the rural lines terminating at the operator's position. The reference letters A, A', A², and A³ represent the rural telephones, only the bells of A', A², and A³ being shown. Associated with each rural line jack, such as J, is a drop similar to that shown in Fig. 1, designated by the reference numeral 2. If more than one operator be employed, the jacks of the rural lines, such as J, may be multiplied to other jacks similar to J', located at the other operators' positions.

Several toll lines may also extend to the operator's position. These lines terminate in jacks similar to jack J, having signal drops similar to drop 2.

Each operator is provided with a plurality of cords, the circuit of which is shown in Fig. 1, designated by the reference character OC. The answering plug is designated by the letter P and the calling plug by the letter P'. A ringing and listening key K, monitoring key K' and a ring and dial key K² are provided. The operator's dialling circuit and head set are shown above the cord circuit.

To complete incoming rural calls to automatic subscribers, a group of service trunks, extending from the operator's position to the automatic exchange are provided. The trunk comprising conductors 20 and 21 is one of this group of trunks. These trunks are accessible to the operator at jacks, such as J³, and terminate in line switches, such as C', at the automatic exchange, shown in Fig. 2. These line switches are also of the common rotary type and are identical with the line switch C, described above.

Another group of trunks for completing incoming toll calls is provided. These trunks are similar to the service trunks described above, being accessible to the operator at jacks such as J⁴ in Fig. 1, and terminating in rotary line switches such as C² in Fig. 2 at the automatic exchange. The rotary line switch C² is identical with line switch C described before. The trunk circuits TC² and TC³ of the service and toll trunks, respectively, differ in that the toll trunk circuit TC³ is supplied with repeating coils in place of the condensers as are used in the service trunk circuit TC².

Having described the system and the apparatus in general, a more detailed description of the various operations will be given. For this purpose, the assumption is first made that the rural subscriber at the substation A wishes to obtain connection with an automatic subscriber at substation B'. To initiate a call the subscriber at A turns the crank of his magneto and removes his receiver. Turning the crank of the magneto causes sufficient current to flow to actuate the signal drop 2 over a circuit by way of conductor 10, through the winding of the drop magnet 2, spring 30 and its resting contact, conductor

40, spring 33 and its resting contact, conductor 41, conductor 11, to the magneto at substation A. The actuation of the drop 2 signals the operator who answers the call by inserting the answering plug P into the jack J, whereupon the drop 2 is cut off at spring 30. The operator, on plugging in, throws the key K to the listening position. This operation bridges the operator's head set across the calling line in the usual manner. She receives the number of the automatic subscriber to be called and inserts the calling plug P' into an idle service trunk jack. We may assume this jack to the J³. This operation closes the contact springs 43, and, in addition, completes a circuit for relay 15 from ground by way of springs controlled by armature 19, lower winding of relay 15, sleeve of jack J³, sleeve of plug P', spring 42 and its resting contact, lamp L', to battery. Lamp L' is lighted. Relay 15 operates to open the shunt around the condenser 80 at the normally closed contacts of the springs controlled by armature 18, and to open the shunt around the condenser 81 at the normally closed contacts of the springs controlled by armature 17. The operation of relay 15 also closes a bridge across the conductors 20 and 21, completing the circuit for the line relay 114 of the line switch C' at the automatic exchange. This bridge across the conductors 20 and 21 includes the winding of the polarized relay 16, armature 17 and its working contact, and springs 43. Relay 114 energizes and closes a circuit for the switching relay and stepping magnet in series at armature 118, and connects the test wiper 126 to the junction of switching relay 113 and stepping magnet 115 at armature 117.

In case the trunk upon which the wipers of the line switch are resting is idle, switching relay 113 energizes immediately. Assuming the trunk to be busy, however, switching relay 113 is short circuited from ground at the test wiper, and does not energize. The wipers 125, 126, and 127 are rotated step by step in a buzzer-like manner by the action of the stepping magnet 115, which operates from ground on the busy test contacts encountered by the test wiper 126. When an idle trunk is reached, which will be assumed to be the trunk comprising conductors 150, 151, and 152, the stepping magnet 115 will cease its stepping action and relay 113, being no longer short circuited, energizes in series with stepping magnet 115. Stepping magnet 115 does not operate at this time on account of the high resistance of switching relay 113. The operation of switching relay 113 opens the test circuit and prepares the holding circuit at armature 119, and at armatures 121 and 120 disconnects the line conductors 20 and 21 from the winding of the line relay 114 and ground, and extends them by way of wipers 125 and 127, contacts 133 and 135, conductors 150 and 152, armatures 130

171 and 168 and their resting contacts, to the upper and lower windings of the line relay 153 of the selector D.

The relay 153 of selector D now operates, 5 closing the circuit for the slow-to-release relay 154. Relay 154 energizes and opens the circuit of the release magnet 159 and prepares a circuit for the vertical magnet 158 at armature 163, and at armature 162 places ground on the release trunk 151, closing the 10 usual holding circuit for the switching relay 113 before the slow-to-release line relay 114 drops back.

After plugging in, the operator throws the 15 key K² to the dialling position. This operation removes the original battery at lamp L' from relay 15, but supplies a new source of current at the resistance 50. The operator may now operate the dialling device CD, to 20 send out the impulses necessary to operate the automatic switches at the automatic exchange in accordance with the digits of the required number. Moving the dial from its normal position, in the process of dialling the 25 first digit, closes the contact springs 14. This completes a circuit for the slow-to-release relay 53. Relay 53 energizes and short circuits the operator's receiver at armature 54 and its working contact, and places ground at a point between the battery at resistance 30 50 and relay 15, at armature 55, thereby placing ground on both ends of the lower winding of relay 15. Relay 15 releases, opens the bridge including relay 16, and places a 35 shunt around each of the condensers 80 and 81. The circuit of line relay 153 now includes the dial CD, which was bridged across the conductors of the cord circuit by the operation of key K². On the return of the dial 40 to normal, springs 14 separate and open the circuit for the slow-to-release relay 53. Relay 53 releases and opens the short circuit across the receivers at armature 54, and removes the shunt around relay 15 at armature 55. Relay 15 will again operate to 45 restore the original bridge at armature 17 and remove the shunt around the condensers 80 and 81. The operator's receiver is short circuited during the period of dialling to prevent the impulses from being heard in the 50 receiver.

When the operator dials the first digit of the desired number, the circuit of the line relay 153 is opened a corresponding number 55 of times in the usual manner. Each time the line relay 153 falls back in response to an interruption, a circuit is closed for the vertical magnet 158 which may be traced from ground by way of the resting contact of armature 169 and said armature, armature 161 and its resting contact, armature 163 and its working contact, winding of relay 155, through the winding of the vertical magnet 158 to battery. By the operation of the vertical magnet 158, the wipers 184, 185, and 186 are

raised opposite the proper level of bank contacts, corresponding to the digit dialled. The slow-to-release relay 155 energizes in series with the vertical magnet, retaining its armature attracted throughout the vertical movement. As a result, a circuit is closed from ground on the release trunk 151 by way of armature 164 and its working contact, off normal contacts 172 (which close upon the first vertical step) and interrupter contacts 167, through the winding of stepping relay 156 to battery. The stepping relay 156 energizes and closes a locking circuit for itself at armature 165, and at armature 166, prepares a circuit for the rotary magnet 160. 80

At the end of the vertical movement, slow acting relay 155 deenergizes and completes the circuit of the rotary magnet 160 at armature 164. Rotary magnet 160, upon energizing, advances the wipers 184, 185 and 186 into engagement with the first set of bank contacts in the selected level, and, near the end of this movement, opens the circuit of stepping relay 156 at interrupter contacts 167. The stepping relay 156 deenergizes and opens the circuit of rotary magnet 160 at armature 166. The rotary magnet, in turn, deenergizes and again closes its interrupter contacts 167. In case the trunk terminating in the first set of bank contacts is idle, switching relay 157 energizes immediately. Assuming the trunk to be busy, however, switching relay 157 is short circuited by the ground potential encountered by test wiper 185. Stepping relay 156 energizes from this same ground potential and closes the circuit of the rotary magnet 160 a second time. The switch wipers are thus rotated into engagement with the next set of bank contacts. This alternate operation of stepping relay 156 and rotary magnet 160 continues until an idle trunk is reached, which may be assumed to be the trunk terminating in bank contacts 187, 188 and 189. Switching relay 157, being no longer short circuited by a ground on the test wiper 185, energizes in series with stepping relay 156. The stepping relay 156, however, does not energize at this time on account of the high resistance of switching relay 157. The operation of relay 157 opens a point in the testing circuit and prepares the holding circuit at armature 170; disconnects ground from armature 161 of the line relay 153 at armature 169; and at armatures 171 and 168, disconnects conductors 150 and 152 from the windings of line relay 153, and extends them by way of wipers 184 and 186 and bank contacts 187 and 189, normally closed springs controlled by armatures 231 and 232 to the upper and lower windings of line relay 211 125 and the rotary connector E.

Line relay 211 of rotary connector E operates by reason of the bridge across the conductors 20 and 21 and completes the circuit for the release relay 212 at armature 234, 130

Release relay 212 energizes; opens a point in the circuit of the release magnet 221 and prepares a circuit for the vertical magnet 222 at armature 235; and places ground potential 5 on the release trunk conductor 188 and on the holding conductor 209 at armatures 236 and 237, respectively.

- When the operator dials the second digit of the desired number, the dial CD is bridged 10 across the trunk in place of relay 16 the same as before. Each time the line relay 211 falls back in response to an interruption produced by the dial, a circuit is closed for the vertical magnet 222. This circuit may be traced from 15 ground by way of armature 234 and its resting contact, armature 235 and its working contact, off normal springs 262 and 264, winding of the slow-to-release series relay 213, through the winding of vertical magnet 222. 20 The above is the circuit over which the first impulse is sent. Upon the first vertical step of the switch, the off normal springs are shifted, so the remaining impulses to the magnet traverse a new circuit which is the same as 25 the one traced above except that it includes the off normal springs 262 and 263, and armature 238 and its working contact, relay 213 now being in an operated position. The vertical magnet 222 operates to raise the switch 30 wipers 270-273, inclusive, step by step until they are placed opposite the level of bank contacts in which is located the set of contacts associated with the line of the substation B'. The slow-to-release relay 213 energizes 35 in series with the vertical magnet 222, and maintains its armature attracted throughout the vertical movement of the switch. At the termination of the vertical movement, relay 213 deenergizes, transferring the operating 40 circuit to the rotary magnet 220.

The operator now dials the third or final digit of the desired number. As before, a series of interruptions is produced in the circuit of the line relay 211. At each retraction of the armature 234 an impulse of current is sent to the rotary magnet 220 over a circuit extending from ground by way of armature 234 and its resting contact, armature 235 and its working contact, off 45 normal springs 262 and 263, armature 238 and its resting contact, resting contact of armature 246 and said armature, winding of slow-to-release relay 217, armature 255 and its resting contact, through the winding of 50 the rotary magnet 220 to battery. The rotary magnet 220 operates to rotate the switch wipers 270-273, inclusive, into engagement with the set of bank contacts associated with the line of the desired substation which has been 55 assumed to be substation B' whose associated bank contacts are 274, 276, and 277. The slow-to-release relay 217 is energized in series with the rotary magnet 220 and maintains its armature attracted throughout the 60 rotary movement. Relay 217, being operated, 65

closes a shunt around the armature 246 and its resting contact, at armature 250; completes a circuit for slow to release relay 218 at armature 249; and holds open a point in the stepping circuit to be described later, at 70 armature 248. Relay 218, in energizing, completes the testing circuit for the busy relay 216, at armature 252.

Should the desired line be busy at the present time, there will be ground potential 75 upon the test contact 276 engaged by the test wiper 272 and as a result the busy relay 216 will be energized. The busy relay 216 operates and prepares a locking circuit for itself at armature 245; opens the initial circuit of the rotary magnet 220 at armature 246; and prepares the busy tone circuit at armature 247. A further result of the operation of busy relay 216 is the closing of 80 a point in the circuit of the stepping relay 215 at armature 244. Shortly after the completion of the impulses, the series relay 217 deenergizes and opens the circuit for the slow-to-release relay 218 at armature 249; opens the circuit for the rotary magnet 220 85 at armature 250; and closes another point in the circuit of the stepping relay 215 at armature 248. This has no utility in setting up a call to the individual telephone as is being described since the contact 275 is not 90 connected to the contact 276, as will be hereinafter described. Since the circuit of the rotary magnet 220 is open at armature 250 and held open by busy relay 216 at armature 246, the wipers are prevented from being 95 rotated off the contacts of the called line by any accidental movement of the dial at the calling substation. Since the circuit of the slow-to-release relay 218 has been opened at armature 249, relay 218 deenergizes, there- 100 by closing the locking circuit for the busy relay 216 by closing the normally closed springs controlled by armature 252 and completing the circuit for the busy tone to the heavy talking conductor 189 at armature 110 253. The busy tone is transmitted through the dial and the tertiary winding of the induction coil N, is induced in the secondary of the coil N, and is reproduced in the operator's receiver, indicating the busy condition 115 on the desired line.

It will be assumed, however, that the line of the desired substation B' is idle at this time. Under these circumstances there will be no ground potential upon the test contact 120 275 engaged by the test wiper 272, no circuit will be completed for the test relay 216 and the operator, not hearing the busy signal, will restore her keys K and K² to normal. Following the deenergization of the slow to 125 release relay 218, a circuit is completed extending from ground on release conductor 188, by way of armature 245 and its resting contact, upper winding of the switching relay 219, resting contact of armature 252, and 130

said armature, test wiper 272, test contact 275, through the winding of switching relay 290 of the line switch C', resting contact of armature 293 and said armature, through 5 the winding of inductor magnet 292 to battery. Relays 219 and 290 are energized over this circuit. However, on account of a mechanical interlocking device controlled by the armature of the line relay 291 which is 10 now normal the armature of the relay 290 is attracted only enough to disconnect the line of the substation B' from its normal battery and ground connections in the line switch C'. The switching relay 219, upon 15 energizing, establishes a locking circuit for itself at armature 258; completes the ringing circuit to the substation B' at armatures 259 and 254; opens a point in the rotary magnet circuit at armature 255; opens a point in the 20 test circuit at armature 257; and places direct ground on the private wiper at armature 258. Ringing current is now intermittently projected over the line of the substation B' from the ringing equipment R.

25 When the called subscriber answers, removing his receiver, a circuit for the ring cut-off relay 214 is completed over the called line loop. Relay 214 energizes and establishes a locking circuit for itself at armature 30 240, and at armatures 239 and 241 cuts off the ring at the resting contacts and finally completes the talking connection at the working contacts. The back bridge relay 210 now supplies talking current to the called 35 substation B', and is immediately energized. The operation of relay 210 reverses the direction of current flow over the calling subscriber's line. This reverses the current in the polarized relay 16, now bridged across the 40 trunk, causing relay 16 to operate. At its armature 19, the operation of relay 16 closes a circuit from ground by way of the working contact spring of armature 19 and armature 19 through the winding of relay 15 to battery. At the resting contact of spring controlled by armature 19, the original energizing circuit for relay 15 over the sleeve of jack J' and plug P', including spring 42 and its resting contact and lamp L', is opened. 45 Relay 15 is held operated by the energization of its upper winding, but lamp L' is extinguished, thereby signalling the operator that the called party has answered. The calling and called parties may now hold conversation.

50 When the conversation is completed, both parties will replace their receivers upon their respective switchhooks. When the receiver is replaced at the called substation B', the back bridge relay 210 is deenergized, reversing the direction of current flow back to its original direction. As a result, the polarized relay 16 falls back again closing the circuit which includes the lower winding of relay 15 55 and lamp L' at the springs controlled by the

armature 19. The lamp L' is lighted, giving the signal to the operator that the automatic subscriber B' has replaced his receiver.

The subscriber at substation A, in addition to replacing his receiver, gives the ring down 70 signal by turning the crank of the magneto a few times. This operation energizes the left hand winding of the ring down relay 13. Relay 13 immediately closes a locking circuit for itself at armature 29, which may be 75 traced from ground by way of the right hand winding of relay 13, armature 29 and its working contact, normally closed springs 31, lamp L to battery. Lamp L is lighted, giving the signal to the operator that the 80 rural subscriber at A has replaced his receiver.

The operator may now release the connection by removing the plugs P and P' from the jacks J and J', respectively. In removing the 85 plug P' from jack J', the circuit for relay 15 is opened. Relay 15 deenergizes and opens the holding bridge across conductors 20 and 21 at armature 17, which causes the deenergization of the line relay 211 and release relay 90 212 of connector E. A circuit is thereby completed for the release magnet 221 which operates to restore the connector to normal. The deenergization of relay 212 also disconnects ground from the release trunk conductor 188 95 and holding conductor 209. As a result of removing ground from the holding conductor 209, the relays 214 and 219 which were held up are permitted to deenergize. The removal of ground from the release conductor 100 permits the switching relays 113 of line switch C' and 157 of the selector D to deenergize. A circuit for the release magnet 159 of the selector D is closed at armature 169. The release magnet 159 operates to restore the selector to normal. The operator 105 also momentarily operates the key K in the cut-off position. The springs 31 are thereby separated, opening the holding circuit for relay 13. The lamp L is extinguished and relay 13 deenergized. All apparatus is 110 again at normal.

Having described the various operations for completing a call from a rural substation to an automatic substation, the operations in connection with completing a toll call to an automatic subscriber will be described. The operation of the automatic switches will be similar to that in the previous case. Consequently a detailed description of the automatic switches will not be repeated, a general description sufficing.

115 As explained before, the toll lines terminate at the operator's position in jacks (not shown) similar to jack J, with drop signals similar to the associated drop signal 2. The operator is given a signal of an incoming toll call by the action of a drop associated with a toll jack. To answer an incoming toll call, the operator inserts the plug P into the calling 120 125 130

toll jack and throws the key K to the listening position. She may now talk to the distant toll operator to obtain the name or number of the desired subscriber. It is assumed that the 5 called substation is substation B'. For toll service, a special group of trunks to the automatic exchange are provided, one of which is the trunk comprising conductors 27 and 28 and the associated trunk circuit TC². After 10 learning the number of the party to be called, the operator inserts the calling plug P' into an idle toll trunk jack, which we may assume to be jack J⁴. This operation closes the contact springs 44, and also completes a circuit for 15 relay 23 which may be traced from ground by way of normally closed springs controlled by armature 24, lower winding of relay 23, sleeve of jack J⁴, sleeve of plug P', spring 42 and its resting contact, and lamp L' to battery. Relay 23 is energized over this circuit and operates to open the shunt around the repeating coil M at armatures 25 and 26 by separating the normally closed contacts of springs controlled by armatures 25 and 26. 20

25 The operation of relay 23 also closes a bridge across the conductors 27 and 28 which includes closed contact springs 44, working contact of the spring controlled by armature 25 and said armature, upper right hand winding of repeating coil M, winding of polarized relay 22, and lower right hand winding of repeating coil M. This bridge across conductors 27 and 28 closes a circuit for the line relay of the rotary line switch C². Line switch C², 30 being similar to line switch C', operates to select a trunk to an idle selector in the same manner as was described in connection with the description of the operation of C'. Assuming trunk comprising conductors 150, 151 and 152 is the trunk selected, the line relay 153 and release relay 154 of selector D energize to prepare the selector for operation. 35

40 After plugging in, the operator throws the key K² in the dialling position. This operation removes battery at lamp L' from relay 23 but supplies a new source of battery at resistance 50, as explained before. The operator may now dial the desired number. Each time the dial is moved from its normal position in the process of dialling, the contact springs 14 are closed. Relay 23 is thereby shunted and deenergized. The dial is then bridged directly across the conductors 27 and 28 ahead of the repeating coil, the original bridge across the line being open at armature 25. 45

50 When the operator dials the first digit of the called number, the selector raises its wipers 184, 185 and 186 to the particular level of contacts which is assigned to the group of connectors having access to the desired substation, and selects a trunk to an idle connector. 55

Assuming the trunk comprising conductors 187, 188, and 189 is this selected trunk, the line

60 relay 211 and release relay 212 energize and 65 prepare the connector E for operation.

65 When the operator dials the second digit, the connector raises its wipers 270-273, inclusive, to the desired level. When the third and 70 last digit is dialled by the operator, the connector rotates its wipers to engage the contacts at which the conductors of the called line 75 terminate. If this line is busy, the busy relay 216 will be energized to give the operator the busy signal. Assuming the line is not busy, 80 the switching relay will energize to complete the connection to the called substation. Ringing current will then be sent out on the line to signal the called subscriber. When the called subscriber lifts his receiver to answer, the 85 ring cut-off relay 214 is energized to cut off the ring and make the final connection between the called subscriber and the incoming toll line. Lifting the receiver at substation B' 90 also causes the operation of the back bridge relay 210, which reverses the direction of current flow in conductors 187 and 189 and through the polarized relay 22. Polarized relay 22 is thereby operated, closing a new circuit for relay 23, which extends from ground 95 by way of the working contact of armature 24 and said armature, upper winding of relay 23 to battery. At springs controlled by armature 24, the original circuit for relay 15, including sleeve of jack J⁴ and plug P', 100 springs 42 and lamp L', is opened. Lamp L' 105 is thereby extinguished, giving the operator a signal indicating that the called subscriber has answered.

110 Should the operator wish to supervise or listen in on the conversation, she may throw her monitoring key K' in the listening position. At springs 45, a circuit is closed for relay 12. Upon energizing, relay 12 opens the transmitter circuit at armature 45; opens the shunt around the receiver and connects the same across the line in series with the two secondary windings of the repeating coil N at armatures 46 and 47; and at armatures 48 and 49 disconnects the grounded impedance coils 115 52 from the listening circuit. The purpose of the impedance coils 52 is to give the listening circuit a ground potential for line testing purposes. Opening the transmitter circuit prevents any office noises from being transmitted to the line. Since the two secondary windings of the repeating coil N are connected in series forming a high impedance, only a minimum amount of voice currents are 120 shunted away from their normal path when the monitoring key K' is thrown and conversation is not interfered with.

125 When the conversation is completed and the talking subscribers hang up their receivers, the operator receives the usual disconnect signals. When the automatic subscriber at B' hangs up his receiver, the back bridge relay 210 of the connector E deenergizes, there-

by reversing the direction of current flow back to normal. The polarized relay 22 releases and closes the circuit for lighting the lamp L'. The originating toll operator at the 5 distant end of the toll line will ring off when the party at her end hangs up. This operates relay 13 which immediately establishes a locking circuit for itself through lamp L, lighting said lamp. The operator now removes the 10 plugs P and P' from their respective jacks and the automatic switches release as described before.

Let us now assume that an automatic subscriber such as B wishes to talk to a rural subscriber. To complete this connection, the subscriber at B must first call the operator. When the calling subscriber at B removes his receiver, a bridge is placed across the conductors 122 and 123, which completes a circuit 20 for the line relay of the line switch C. Line switch C, being similar to line switch C', operates to select a trunk to an idle selector in the same manner as was described in connection with the description of the operation 25 of C'.

Assuming the trunk comprising conductors 150, 151 and 152 is the trunk selected, the line relay 153 and release relay 154 of selector D energize and prepare the selector for operation.

The subscriber at B now dials the number assigned to the rural service trunks. In response to the first digit dialled, the selector raises its wipers opposite the level which has 35 access to that group of connectors in whose banks the trunks for rural service terminate, and then rotates its wipers to select a trunk to an idle connector of this group.

Assuming the trunk comprising conductors 40 187, 188, and 189 is the trunk selected, the line relay 211 and release relay 212 energize immediately, and prepare the connector E for operation.

In response to the impulses of the second 45 digit dialled, the connector raises its wipers 270-273, inclusive, opposite the level of contacts in which the rural service trunks terminate. When the third and last digit is dialled, the connector rotates its wipers into 50 engagement with the contacts of the first trunk.

The operation of the connector from this point is somewhat different than it was in the previous case. In addition to having a 55 vertical and rotary motion, each responsive to impulses corresponding to a digit dialled, the connector has also an automatic rotary motion for selecting the first idle trunk of a group of trunks.

60 This is accomplished in the following manner: In a group of trunks, the test contacts similar to contacts 281 and 282 of each trunk are connected together on all except the last trunk of the group. Thus when a line becomes 65 busy, ground is present upon both

these contacts. Assuming that the first trunk of the group of rural service trunks with which the wipers 270-273, inclusive, are now engaged, is busy, ground will be present on wipers 271 and 272. It will be remembered that relay 217 is energized in series with the rotary magnet 220 and that relay 218 is held operated during the rotary movement over a circuit completed at armature 249 and its working contact. From ground on wiper 75 272, the test relay 216 will be energized as described hereinbefore and will operate to prepare a locking circuit for itself at armature 245 and close a point in the circuit of stepping relay 215 at armature 244. Soon 80 after the termination of the impulses of the last digit dialled, relay 217 falls back and closes a circuit extending from ground on wiper 271 by way of the working contact of armature 251 and armature 251, resting contact of armature 248 and armature 248, working contact of armature 244 and armature 244, armature 265 and its resting contact through winding of stepping relay 215 to battery. Relay 215 energizes and establishes 85 a locking circuit for itself at armature 242 and completes the circuit of the rotary magnet 220 at armature 243. Relay 218 is also maintained operated in parallel with the rotary magnet. Magnet 220 attracts its armature 265, thereby rotating the connector wipers into engagement with the next set of bank contacts of the selected level, and opening the locking circuit of the stepping relay 215. Relay 215 falls back and breaks the 90 circuit of the magnet 220 thereby deenergizing magnet 220.

If this next trunk line is busy, the stepping relay 215 will again energize from ground on test wiper 271 and the connector 105 switch wipers will be rotated into engagement with the contacts of the third line of the group. The alternate operations of the stepping relay 215 and the rotary magnet 220 will continue until an idle line in the 110 group is found or until the switch wipers are rotated into engagement with the last line in the group. If the last line is also busy, there will be ground potential present only upon the test contact engaged by the test 115 wiper 272, since the test contacts of the last line of the group similar to 281 and 282 are not joined together, and the stepping relay cannot again be energized. The test relay 216 will remain operated, however, and a 120 busy tone will be given to the calling subscriber in the same manner as was described hereinbefore.

It will be assumed that the trunk comprising conductors 32, 33 and 34 terminating in 125 contacts 280, 281, 282, and 283 is the first idle trunk of the group of rural service trunks. In this case there will be no ground potential upon the test contacts 281 and 282 engaged by the test wipers 271 and 272. Con- 130

sequently, test relay 216 will deenergize and stepping relay 215 will not be energized. As a result, the circuit for the rotary magnet 220 and relay 218 in parallel is opened at 6 armature 243. Following the deenergization of the slow acting relay 218, a circuit is completed extending from ground on release conductor 188 by way of armature 245 and its resting contact, upper winding of the 10 switching relay 219, resting contact of armature 252 and said armature, test wiper 272, test contact 282, conductor 32, resting contact of armature 8 and said armature through winding of relay 5 to battery. Relays 5 and 15 219 are energized over this circuit. The switching relay 219 operates and establishes a locking circuit for itself and completes a circuit for ringing current over the conductors 33 and 34, as described hereinbefore. 20 Relay 5, upon energizing, prepares the bridge including the upper winding of relay 4, and normally open contact springs 62. Ringing current over conductors 33 and 34 operates the drop magnet 3 over a circuit which extends from conductor 34 through winding of drop magnet 3, normally closed contact springs 61, and through condenser 84 to conductor 33. The release of the drop signals the operator who inserts the answering plug 25 30 P into the jack J^2 . This operation opens the circuit for the drop magnet 3 at springs 61, and closes the bridge across the conductors 33 and 34 at contact springs 62. Relay 4 and ring cut-off relay 214 are energized over this 35 circuit. Relay 4 operates to remove ground from the sleeve of the jack J^2 at armature 7, and opens the circuit of slow-to-release relay 5 at armature 8. The ring cut-off relay 214, upon energizing, establishes a locking circuit 40 for itself and cuts off the ring and finally completes the talking connections as previously described. After the ring cut-off relay 214 has established its locking circuit, relay 5 falls back and, at armature 9, opens the 45 shunt around the high resistance lower winding of relay 4. The back bridge relay 210 may or may not operate before this shunt is removed, depending largely on the adjustment of relay 5, but after the back bridge relay 210 is in series with the two windings of relay 4, the current flow is insufficient to operate relay 210 or hold it in operation if it be operated. 50

Ordinarily, in a connection between one 55 automatic subscriber and another automatic subscriber, the release of the selector is under the control of the calling party, but the connector is released by the party last to hang up his receiver, which may be either the called or calling party. When the calling party replaces his receiver first, the line relay 211 and release relay 212 are deenergized, but the connector is held up by the energization of the back bridge relay 210 which supplies 60 ground to the holding conductor 209 at arm-

ture 230, and holds the circuit of the release magnet open at armature 233. In a connection of the type being described, namely, from an automatic subscriber through an operator's switchboard, it is necessary that the release of both the selector and connector be under the control of the calling automatic subscriber's switchhook, to give the operator supervision. By preventing the back bridge relay, such as relay 210 of the connector E, from operating on calls to the operator, the connector, as well as the selector, is released as soon as the calling subscriber replaces his receiver, giving the operator supervision as will be described hereinafter. 70 75 80

After plugging in, the operator throws the key K to the listening position and may then hold conversation with the calling subscriber and obtain the number of the rural subscriber with which connection is desired. 85

Assuming substation A to be this desired party, the operator tests the line to substation A in the usual manner by touching the tip of plug P' to the sleeve of jack J. If this line to substation A, comprising conductors 90 10 and 11, is busy through one of the other operator's cords, there will be battery potential present on the sleeve at a lamp similar to L' of cord circuit OC. Because of the ground potential on the talking strands of the cord at 95 the impedance 52, there will be a sudden drop in potential across the operator's receiver, causing the click in the receiver which indicates a busy line. 100

Assuming the line to substation A is idle, the operator, hearing no click when testing, inserts the answering plug P' into jack J and throws the key K² to the ringing position one or more times in accordance with the proper code to signal the substation A. The operator keeps her listening key depressed until the subscriber A answers. When the two parties begin conversing, she may release the listening key. 105

At the end of the conversation, both parties 110 will replace their receivers on their respective switchhooks. Subscriber A, in addition to replacing his receiver, rings off in the usual manner, as described hereinbefore. The ring-down relay 18 is thereby energized, closing a locking circuit for itself and lighting the disconnect signal lamp L. When subscriber B replaces his receiver, the bridge across the talking conductors 122 and 123 is 115 opened. Relays 211 and 212 of the connector fall back, thereby removing ground from the release conductor 188 and holding conductor 209 and closing the circuit for the release magnets of the selector D and connector E as described before. The release of connector 120 E, by disengaging its wipers from contacts 280-284, inclusive, opens the circuit for the relay 4. Relay 4, upon deenergizing, closes a circuit extending from ground at resistance coil 6, by way of armature 7 and its resting 125 130

contact, sleeve of jack J^2 , sleeve of plug P, through lamp L' to battery. The lamp L' is lighted over this circuit indicating to the operator that the subscriber at substation B has 5 replaced his receiver and that she may pull down the connection.

Provisions have been made for giving the automatic subscribers outgoing toll service. To make a long distance call an automatic 10 subscriber, such as B, removes his receiver and dials the code number for long distance service. Connection is extended through the line switch C, a selector and connector, such as D and E to an idle trunk of a group of toll 15 trunks, which is similar to the trunk comprising conductors 32, 33 and 34, terminating at the operator's switchboard in the jack J^2 and trunk circuit TC' .

The operator answers the call as described 20 in the previous case, and obtains the name or number of the distant substation with which connection is desired and the number of the calling automatic subscriber. The operator records this information on a ticket 25 and informs the calling subscriber that she will call him when she has obtained connection with the distant substation. The subscriber at substation B may now replace his receiver, thereby releasing the connection.

30 The operator proceeds to establish the long distance connection. When notified of the completion of the connection to the distant subscriber, the operator recalls the automatic subscriber at substation B over one of the 35 toll service trunks similar to the trunk comprising conductors 27 and 28. The connection is extended through the automatic switches, such as the line switch C, the selector D, and the connector E, containing the 40 bank contacts 130, 131, and 132, to the substation B. The subscriber at substation B may now converse with the distant subscriber.

45 At the termination of the conversation, the subscriber at B replaces his receiver. The lamp L' is thereby lighted as described hereinbefore, indicating to the operator that she may disconnect. Before removing the plug P from the toll trunk jack, she gives the 50 disconnect signal to the distant toll operator by throwing the key K in the ringing position for a short interval.

In order to explain another method for 55 completing a toll call, especially to a station easily obtainable, it will be assumed that a subscriber, as B, again calls the operator, as described above. The operator, after obtaining the number of the desired distant subscriber, may instruct the calling subscriber, 60 B to hold the connection, keeping the plug P in the jack of the toll recording trunk. By inserting the plug P' into the jack of an outgoing toll line, she may proceed to complete the connection in the usual manner. 65 As soon as the connection is completed, the

operator notifies the calling subscribers who may then commence conversation with the distant subscriber. The method just described is similar to the method followed in 70 extending calls to rural lines.

An automatic subscriber at a substation such as B may wish to call the operator for information or for complaint. By dialling the code number for information or complaint service, connection is obtained to the 75 operator over one of the information or complaint trunks which is similar to the trunk comprising conductors 32, 33, and 34, terminating at jack J^2 and trunk circuit TC' , 80 the manner of connection being similar to that described hereinbefore.

Any automatic subscriber may, of course, 85 call any other automatic subscriber. A connection from the substation B to substation B' extends through the line switch C, a selector such as D, and a connector such as E, in whose banks the line to the substation B' terminates.

What is claimed is:

1. In a telephone system, a trunk extending 90 from a manual jack to an automatic switchboard, said trunk comprising two inductively connected sections, a cord circuit for connecting with said jack, a calling device and means for bridging the same across the talking strands of said cord circuit, and means responsive each time said calling device is operated for conductively connecting the two sections of said trunk line together to enable said calling device to control the 95 switches at the said automatic switchboard over said trunk.

2. In a telephone system a cord circuit and 100 trunk line temporarily connected by a plug and jack, said trunk line comprising two inductively connected sections, a bridge across one section, a calling device bridged across said cord circuit, and means operated automatically each time the calling device is set 105 for opening said first bridge and for bypassing said inductive connections so that the calling device can transmit impulses over the trunk line on restoring to normal.

3. In a telephone system, a cord circuit and 110 trunk line temporarily connected by a plug and jack, said trunk line comprising two inductively connected sections, circuits for conductively connecting said sections; a relay in the trunk held energized over the sleeve of said jack to hold said circuits open, and means associated with the cord circuit for shunting said relay to deenergize the same.

4. In a telephone system, a cord circuit and 115 trunk line temporarily connected by a plug and jack, said trunk line comprising two inductively connected sections, circuits for conductively connecting said sections, a relay in the trunk held energized over the sleeve 120 of said jack to hold said circuits open, a 125 calling device associated with said cord circuit,

- cuit, said calling device having a dial, and means responsive to the movement of said dial from normal position for shunting said relay to deenergize the same.
5. In a telephone system, a cord circuit and trunk line temporarily connected by a plug and jack, said trunk line comprising two inductively connected sections, circuits for conductively connecting said sections, a relay 10 in the trunk held energized over the sleeve of said jack to hold said circuits open, a calling device bridged across the cord circuit, off normal springs actuated in the operation of said calling device, and means controlled by said springs for deenergizing said relay.
6. In a telephone system, a temporarily established connection including a cord circuit and a jack ending trunk circuit, a signal in the cord circuit and a relay in the trunk 20 circuit energized in series over a circuit including the sleeve of said jack, a supervisory relay bridged across said trunk circuit by the energization of said first relay, contacts on said supervisory relay for opening the sleeve circuit to restore said signal, a second circuit for holding said first relay energized while the sleeve circuit is open, said second circuit excluding the winding of said first relay which is included in said first circuit.
7. In a telephone system, a temporarily established connection including a cord circuit and a jack ending trunk circuit, a signal in the cord circuit and a relay in the trunk circuit energized in series over a circuit including the sleeve of said jack, a second circuit for said relay, and a relay connected with the trunk by said first relay and controlled thereover to open the sleeve circuit and close the said second circuit, whereby the signal is restored without restoring said first relay.
8. In a jack ending trunk circuit, two condensers inserted in the two talking leads, respectively, a relay having a circuit including the sleeve of said jack, shunt circuits for said condensers controlled by said relay, a supervisory relay arranged to be bridged across the trunk by the operation of said first relay, contacts on said supervisory relay for opening the said sleeve relay circuit, and a local circuit 40 for said sleeve relay also controlled by said supervisory relay.
9. In a jack ending trunk circuit comprising two inductively connected sections, a relay controlled over the sleeve of said jack, contacts on said relay for opening and closing conductive connections between said sections, and a second relay controlled over one of said conductive connections for controlling said first relay independent of the sleeve of said 50 jack.
10. In combination, a cord circuit, a battery for supplying current, a sleeve conductor connected to a supervisory signal, the other terminal of which is connected to one pole of the
- battery, a calling device, a key for associating said device with the talking strands of said cord circuit, said key having contacts for shifting said sleeve conductor from said signal to a similarly connected resistance, and a relay responsive to the operation of said calling device for connecting the said sleeve conductor to the other pole of the battery.
11. In a telephone system, a trunk line terminating in a jack at a manual switchboard, a relay individual to said trunk line, a second 70 relay controlled over the sleeve of the jack for bridging said first relay across the talking conductors of said trunk line when a plug is inserted in said jack, a battery, a conductive connection from one pole of the battery to the 75 sleeve of said jack, and contacts on said first relay for disconnecting said battery from the sleeve of said jack and for closing a local circuit for said second relay.
12. In a telephone system, a temporarily 80 established connection including an automatic connector switch, a trunk line seized by such switch, and a manual cord circuit, the trunk line and cord circuit being connected through a plug and jack, a signal in said cord circuit 85 having a circuit including the sleeve of said jack, and a relay individual to said trunk line held energized thereover by current supplied from said switch to hold the circuit of said signal open.
13. In a telephone system, a trunk line extending to a jack at a manual switchboard, a connector switch for connecting with said trunk line, said connector including means for projecting ringing current over said trunk 100 line to signal the operator, a battery feed relay and a ring cut-off relay in said connector, a double wound relay individual to the trunk line having high and low resistance windings in series, a slow acting relay energized when the connector connects with said trunk line to short circuit said high resistance winding, means for bridging said double wound relay across the trunk line when the operator responds, said double wound relay thereupon 105 having its low resistance winding energized in series with the said ring cut-off relay, contacts on said ring cut-off relay for bridging said battery feed relay across the connected trunk line, and contacts on said double wound relay for opening the circuit of said slow acting relay, whereupon the latter is deenergized to remove the short circuit from said high 110 resistance winding to prevent the energization of said battery feed relay.
14. In a telephone system, a cord circuit and a trunk line temporarily connected by a plug and jack, said trunk line comprising two sections, a repeating coil for inductively connecting said sections, a calling device bridged across said cord circuit, and means operative 115 each time the calling device is set for conductively connecting said sections independent 120 of the trunk line.

of said repeating coil so that the calling device can transmit impulses over the trunk line on restoring to normal.

15. In a telephone system, a cord circuit and a trunk line temporarily connected by a plug and jack, said trunk line comprising two sections, a repeating coil, circuit connections for said repeating coil for inductively connecting said sections, a relay in the trunk held energized over the sleeve of said jack for maintaining said circuit connections intact, and means associated with the cord circuit for deenergizing said relay to disconnect said repeating coil and conductively connect said sections.

16. In a telephone system, a cord circuit and a trunk line temporarily connected by a plug and jack, said trunk line comprising two sections, a repeating coil inductively connecting said sections, circuits for conductively connecting said sections, a relay in the trunk held energized over the sleeve of said jack to hold said circuits open, a calling device associated with said cord circuit, and means responsive to the movement of said device from normal position for shunting said relay to deenergize the same.

17. In a telephone system, a cord circuit and a trunk line temporarily connected by a plug and jack, said trunk line comprising two sections, a repeating coil inductively connecting said sections, circuits for conductively connecting said sections, a relay in the trunk held energized over the sleeve of said jack to hold said circuits open, a calling device bridged across the cord circuit, off normal springs actuated in the operation of said calling device, and means controlled by said springs for deenergizing said relay.

18. In a jack ending trunk circuit, a repeating coil dividing said trunk circuit into two inductively connected sections, a relay having a circuit including the sleeve of the jack of said trunk circuit, circuit connections for conductively connecting said sections controlled by said relay, a supervisory relay connected in series with a winding of said repeating coil, contacts on said supervisory re-

lay for opening the said sleeve relay circuit, and a local circuit for said sleeve relay also controlled by said supervisory relay.

19. In a jack ending trunk circuit comprising two sections, a repeating coil for inductively connecting said sections, a relay controlled over the sleeve of the jack of said trunk circuit, contacts on said relay for opening and closing conductive connections between said sections, and a second relay controlled over one of said conductive connections for controlling said first relay independent of the sleeve of said jack.

20. In a jack ending trunk circuit comprising two sections, a repeating coil for inductively connecting said sections, a relay controlled over the sleeve of the jack of said trunk circuit, contacts on said relay for opening and closing conductive connections between said sections and for disconnecting said repeating coil whenever said conductive connections are closed, and a second relay controlled over one of said conductive connections for controlling said first relay independent of the sleeve of said jack.

21. In combination, a cord circuit, an operator's telephone set adapted to be connected to said cord circuit, two retard coils connected in series across the talking leads of said telephone set, a battery connected to the junction of said two retard coils, and a relay for disconnecting said two retard coils from the talking leads of said telephone set.

22. In combination, a cord circuit, an operator's telephone set, a listening key for connecting said telephone set with said cord circuit, two retard coils connected in series across the talking leads of said telephone set, a monitoring key for connecting the receiver of said telephone set to said cord circuit independent of the transmitter of said telephone set, and means controlled by said monitoring key for disconnecting said retard coils from said talking leads.

In witness whereof, I hereunto subscribe my name this 12th day of January, A. D., 1925.

THOMAS F. CROCKER.
